DESIGN FOR A FOOT STAND

John L. McLane, Jersey City, N. J.

Application September 16, 1944, Serial No. 115,316

Term of patent 7 years

(Cl. D15—8)

To all whom it may concern:

Be it known that I, John L. McLane, a citizen of the United States, residing at Jersey City, in the county of Hudson and State of New Jersey, have invented a new, original, and ornamental Design for a Foot Stand, of which the following is a specification, reference being had to the accompanying drawing, forming part thereof.

I claim:

The ornamental design for a foot stand, as shown.

JOHN L. McLANE.
